WINDOW STRUCTURE

Paul T. Keebler, Pittsburgh, Pa., assignor to
 B. & G. Manufacturing Company, Pittsburgh,
 Pa., a corporation of Pennsylvania

Application January 19, 1952, Serial No. 267,236

6 Claims. (Cl. 20—55)

1

My invention relates to storm windows which are mounted to enclose the usual windows of a building and has particular relation to storm windows of the type adapted to be mounted on casement windows.

A storm window constructed in accordance with the teachings of the prior art of which I am aware consists of a rigid transparent assembly adapted to be securely mounted either inside or outside of a building on the frame of a building window which it is to enclose. The frame of the storm window assembly is sealed to the frame of the building window; but the joint includes breather vents, and particles of soot, dirt and other foreign materials seep in through the vents with the air which circulates between the windows and become deposited on the transparent surfaces which bounds the space between the windows. It is essential that both surfaces of the building window and the storm window be cleaned periodically. The external surfaces of both windows can be handled with facility but the surfaces bounding the space between the windows is not readily accessible.

In cleaning storm windows constructed in accordance with the teachings of the prior art, it is necessary to remove the storm window entirely from the building window. Such removal involves serious inconvenience and difficulty, and often, because of the ineptness of the person who cleans the windows, may result in fracture of either the storm window or the building windows.

It is, accordingly, an object of my invention to provide a storm window assembly which shall readily permit cleaning of the surfaces bounding the space between the building window and the storm window without removal of the storm window from the building window.

Another object of my invention is to provide a storm window assembly which when in use may be readily cleaned completely without serious inconvenience or difficulty.

A further object of my invention is to provide a novel storm window construction.

An ancillary object of my invention is to provide a novel hinge.

In accordance with my invention, I provide a storm window assembly in which the transparent portion of the storm window is hinged to the frame on which it is supported. This frame is designed to be secured to the frame of the building window and the hinge assembly in accordance with my invention, is so conceived that its bearing is provided in the frame of the storm window and its hinge rod is secured to the transparent portion of the window.

2

The storm window is repeatedly opened and closed during cleaning and is otherwise subject to substantial wear. In accordance with a specific aspect of my invention, then, the hinge is of sturdy construction including a single hinge rod which extends throughout the length of the bearing. Such a long rod would have a tendency to bind but this tendency is suppressed by thrust bearings provided at both ends of the rod. The hinge bearing is provided with a positive stop which prevents the window from swinging over too great an angle. This stop positions the storm window conveniently for cleaning and prevents damage to it by its abruptly being thrown open by an attendant.

Storm windows of the type involved in my invention are preferably composed of aluminum or aluminum alloys. Such metals have a tendency to oxidize. To suppress any locking or binding effect by reason of the oxidation, the hinge rod, in accordance with my invention, is provided with scraper edges which remove any oxidation from the bearing. The hinge rod is also provided with grease grooves so that the bearing is maintained well lubricated.

The entire hinge is mounted within the frame of the storm window assembly and there are no external projections. The transparent portion of the storm window is maintained closed by a spring loaded latch which firmly holds this portion against the frame.

The novel features that I consider characteristic of my invention is set forth with particularity and in the appended claims. My invention itself, however, both as to its organization and its method of operation, together with additional objects and advantages thereof will be understood by reference to the following description and to the drawings, in which:

40 Figure 1 is a view in front elevation from the outside of a building of a storm window in accordance with my invention;

Fig. 2 is a section taken along line II—II of Fig. 1;

Fig. 3 is a section taken along line III—III of Fig. 1;

Fig. 4 is a view in perspective, partly exploded, showing the hinge rod assembly in accordance with my invention;

50 Fig. 5 is a view in front elevation from the outside of the building of a portion of the storm window in accordance with my invention with a part broken away;

Fig. 6 is a view in front elevation of another portion of the storm window in accordance with my invention with a part broken away; and

Fig. 7 is a fragmentary view partly in section showing a modification of my invention.

The structure shown in the drawing comprises a supporting frame 7 adapted to be mounted on the frame 9 of the building window 11 to be covered. The frame 7 is of rectangular shape and has four sides 13, 15, 17 and 19. The sides are of composite contour but of generally trapezoidal longitudinal cross section, the ends being at an angle of 45° to the longest side. The dimensions of the sides are such that the shorter sides 17 and 19 may be disposed between the longer sides 13 and 15 in edge-along-edge engagement. One edge each of the sides 17 and 19 are brazed to the edges of the side 13 and the other edges of each are held in engagement with the side 15 by corner gussets 21 which are staked at 23. A rigid frame is thus formed.

While the frame shown in the drawings is brazed at two corners and gusseted at the other two, frames formed in other ways are within the scope of my invention. All four corners of the frame may be brazed or all four corners may be gusseted.

The long side 13 of the frame 7 consists of an elongated rectangular strip 25 along which a hollow slot or channel 27 having the cross section of the segment of a circle extends. A supporting flange 29 projects from one edge of strip 25, and a strip 31 of substantial area extends from the other end. The flange 29 and the strip 25 together constitute a right angle bracket. The flange 29 connects with the strip 25 through a web 33 at right angles with it which is integral with the flange on one side and with the strip on the other. There is a notch 35 which serves a breather vent in the web 33. The flange 29 has bevelled edges and when mounted on the building window is sealed into a suitable plastic seal 37, which securely engages the frame 9 of the building window. The flange 29 is also secured to the frame 9 of the building window by a plurality of machine screws 39.

The other long side 15 of the frame 7 consists of a similar strip 41 having a hollow slot or channel 43 from which a supporting flange 45 projects. As in the case of the other side, a web 47 extends between the flange 45 and the strip 41 and includes a breather vent 49. The strip 41 also has a lip 51 of substantial area. The shorter sides 17 and 19 are also provided with flanges 53 and 55, respectively, which are sealed to the frame 9 of the building window in the same manner as the flanges 29 and 45 of the longer sides 13 and 15.

The transparent portion of the storm window consists of a frame 59 within which a translucent surface 61 such as glass is sealed. This frame 59 is mounted on the supporting frame 7 in such manner that sides 63, 65, 67 and 69 of the window frame are parallel to corresponding sides 13, 15, 17 and 19, respectively, of the supporting frame 7, and one of the surfaces each of the sides 63 and 65 rests against the lips 31 and 51, respectively.

The frame 59 is joined to the long side 13 of the supporting frame 7 through a hinge rod which is of generally circular section and is pivotally mounted in the slot 27 of this side. A bracket 73 extends between the hinge rod 71 and the corresponding side 63 of the window frame 59; the bracket 73 is integral with the hinge pin 71 and is secured to the frame 59 by screws 75 holding the frame 59 against the lip 31. This bracket 73 is bent substantially at right

angles between its junction with the hinge rod 71 and its mounting on the frame 59. The boundary 76 of the slot 27 remote from the frame 59 is at an acute angle to the adjacent surface 77 of the bracket 73 and when the bracket is rotated with the hinge rod 71 it engages this surface 76 and is stopped from pivoting beyond it. The angle between the surfaces 76 and 77 is such that the storm window 61 may be pivoted out to a convenient position for cleaning and the coaction of the surfaces 76 and 77 holds the storm window in this position while it is being cleaned.

The hinge rod is provided with one or more grooves 79, the sides of which terminate abruptly at the slot 27. As the hinge rod rotates, the engagement of the edges of these grooves 79 with the slot tend to clean the slot, removing oxides and other foreign particles. The grooves 79 also serve for lubrication purposes holding a lubricant between the rod 71 and the slot 27.

The hinge rod 71 extends along the whole length of the slot 27 and to prevent binding of the long hinge rod, bronze end bearing studs 81 and 83 are provided. These studs 81 and 83 engage the ends of the hinge rod on one side and the adjacent edges of the sides 17 and 19, respectively, of the supporting frame on the other.

Where a gusseted structure to the side 13 is used, the ends of the gussets projecting along side 13 may serve as thrust bearings. This structure is shown in Fig. 7. In Figure 7 the ends of hinge rod 71 are shown as bearing simultaneously against the ends of gussets 21, which are located partially within the channel or slot 27. Here, the gussets 21 perform the function of end bearings 81, 83 in Figure 4.

On the opposite side 67, the frame of the window is provided with a latch 87. This latch 40 comprises a pin 89 which is slidably mounted in the frame 59 near the center of the side 67 and carries at its external end a cup shaped projection 91 rigidly secured thereto. The pin projects through a notch in the lip 51. This pin 45 is held in its outermost position by a spring 93 which engages the inner surface of the cup 91 at one end and a washer 95 secured to the side 59 at the other. At its internal end, the pin carries a locking hook 97 which engages the lip 51 extending from the strip 41 and under the action of the spring 93 holds the frame 59 in engagement with the strip 41.

With the hook 97 engaging the lip 51 of the adjacent strip 41, the window is in the closed 55 position. The hook 97 may be disengaged from the strip 41 by compressing the cup-shaped portion 91 and turning it. The window assembly 60 may then be pivoted outward to the angle determined by the limiting stop 76. The surfaces of the building window 11 and the storm window 61 which bound the space between the windows may thus be readily cleaned without damage to either of the windows.

The storm windows may be mounted to pivot 65 in different ways depending on the structure of the building windows. A storm window may swing about the edge (9) of a building window along which the building window is pivoted, that is, the hinge of the storm window may be substantially coaxial with the hinges of the building window. Such an arrangement is used where two building windows covering an opening are arranged to swing away from their joint, one clockwise and the other counterclockwise. The 70 storm window may also be arranged to swing

about a hinge mounted along the edge of the building window which is opened. Such an arrangement is used where the building windows which open are disposed adjacent a picture window and the sides of the building windows along the picture window swing away from the picture window. Where a storm window covers a transom window, the storm window may be horizontally hinged. The storm window for a picture window is also customarily horizontally hinged with the storm window swinging upward from the lower side of the picture window.

An important feature of my invention is the continuous hinge. This hinge has a length corresponding to the length of the side of the building window along which it is mounted. For long storm windows it is correspondingly long. The hinge therefore is in all situations capable of supporting the storm window.

While I have shown a certain specific object of my invention, I am fully aware that many modifications thereof are possible. My invention, therefore, is not to be limited except insofar as is necessitated by the prior art and by the spirit of the appended claims.

I claim as my invention:

1. A storm window structure for a casement type window, comprising, a window frame of generally rectangular outline, said window frame including means for securing said window frame immovably to a building structure in a plane parallel to the plane of the building structure and offset therefrom, said window frame comprising a plurality of flanged brackets, said brackets each including a flange extending in a plane parallel with said building structure, each of said brackets further including a strip extending from said flange in a direction perpendicular with said building structure, one of said strips terminating remotely of said building structure in a hinge post extending parallel to said building structure and of substantially rectangular transverse cross section, said hinge post having only a single longitudinal channel extending along the entire length of said hinge post, said channel having a cross section in the form of an arc of a circle subtending an angle of greater than 180° and facing away from the building structure, a rectangular sash frame set into said window frame, a transparent panel set into said sash frame, a hinge rod of generally circular transverse cross section secured to the said sash frame at one side thereof, said hinge rod substantially co-extensive with said channel and snugly and rotatively seating within said channel, and means for positioning said hinge rod longitudinally of said channel consisting of end bearings for the ends of said hinge rod located within said channel at opposite ends thereof, said hinge rod extending the entire distance between said end bearings.

2. The combination in accordance with claim 1 wherein said hinge rod includes at least one groove in its outer surface, said at least one groove extending along substantially the entire length of said hinge rod, said at least one groove having sharp edges, said hinge post and hinge rod being fabricated of aluminum, whereby said sharp edges remove oxide of aluminum during rotation of said hinge rod.

3. A storm window sash for a casement window structure comprising, a rectangular window frame, a rectangular sash frame set into said window frame, said window frame having four frame members adjacent ones of which extend mutually at right angles, at least one of said window frame members having a longitudinal channel extending along its entire length, said channel having the transverse cross section of a segment of a circle subtending an arc of greater than 180°, a plurality of gussets, each of said gussets securing together an adjacent pair of said window frame members, each of said gussets extending into a different end of said channel, a hinge rod located within said channel and rotatable therein, means rigidly securing said hinge rod to one side of said sash frame, said hinge rod extending between said gussets, and said gussets providing end bearings for said hinge rod.
4. A storm window structure for a casement window comprising a rectangular window frame, a rectangular sash frame set into said window frame, said window frame having four frame members adjacent ones of which extend mutually at right angles, at least one of said frame members having a longitudinal channel extending along the entire length thereof, said channel having the transverse cross section of a segment of a circle making an arc greater than 180°, a plurality of end bearing members fixed at opposite ends of said channel and at least partially in said channel, a hinge rod located within said channel and rotatable therein, means for rigidly securing said hinge rod to one side of said sash frame, said hinge rod extending between both of said end bearing members in simultaneous end bearing relation thereto.
5. The combination in accordance with claim 4 wherein is provided a longitudinally extending groove in said hinge rod, said groove adapted to contain lubricating material and provided with edges of sufficient sharpness to remove foreign particles encountered by said edges during rotation of said hinge rod.
6. The combination in accordance with claim 5 wherein said end bearing members are gusset elements arranged to secure together adjacent and mutually perpendicular ones of said window frame members.
